UNITED STATES PATENT OFFICE.

JOSEPH A. GROEBLI, OF NEW YORK, N. Y.

BEAD-SEWING MACHINE.

Application filed February 18, 1921. Serial No. 445,943.

To all whom it may concern

Be it known that I, JOSEPH A. GROEBLI, a citizen of the United States, and a resident of the city, county, and State of New York, 5 have invented certain new and useful Improvements in Bead-Sewing Machines, of which the following is a specification.

My invention relates to that class of bead-sewing machines which may be designated as single thread machines, that is machines whereby the beads are secured to a fabric by the same thread upon which they are strung. A machine of this general class is described in my Letters Patent of 15 the United States, No. 1,356,762, dated October 26, 1920. And my present improvements are particularly directed to means whereby the feeding of the beads along the thread, and their delivery, one at a time, 20 upon the fabric may be accomplished with increased accuracy and precision, thereby increasing the efficiency of the machine, and securing a better product therefrom, all as is hereinafter more fully pointed out and 25 claimed.

In the drawings, Fig. 1 is a side elevation of a machine embodying my improvements; Fig. 2 is a side elevation, taken as in Fig. 1, and on an enlarged scale, of a portion of 30 the fabric feeding and stitch forming mechanism; Fig. 3 is a front elevation looking to the right on Fig. 2; Fig. 4 is an elevation taken from the side opposite to that shown in Fig. 1, on 35 the same scale as Fig. 2 of the upper portion of the mechanism; Fig. 5 is a top view, on an enlarged scale as compared with Fig. 1, of the thread carrying and bead feeding mechanism; Fig. 6 is a similar view, 40 on the same scale as Fig. 4, of the bead feeding mechanism, the bead trough being broken away; Fig. 7 is a side elevation, looking up on Fig. 6; Fig. 8 is a cross sectional view, taken on the line 8—8 of Fig. 45 2 looking to the left; Fig. 9 is a side elevation on a much enlarged scale, of the looper, bead separator and attachments shown in Figs. 1, 2 and 3; Fig. 10 is a cross sectional view of the same, taken on the line 50 10—10 of Fig. 9, looking up; Fig. 11 is a

view similar to Fig. 10, but showing the looper and bead follower in their initial positions, for beginning a stitch; and Fig. 12 is a detail showing the relative positions of the looper and bead follower, taken 55 looking upon Fig. 9.

Similar letters of reference designate corresponding parts in all the figures.

The base plate 1 of the machine is provided with the usual bracket 2 and arm 3 60 to carry the mechanism located above the base plate; while the needle and nipple operating mechanism and the lower elements of the feed directing control are carried in suitable brackets as 4, 5, 6, attached below the base 65 plate.

The driving shaft 7, through beveled gears 8, 9, shaft 10, beveled gears 11, 12, shaft 13, eccentric pin 14 and sliding bracket 15, reciprocates the needle carrier 16 in the 70 usual manner; and, also, through the eccentric 17, bell crank 18, engaging with the sliding bracket 19, reciprocates the needle nipple 20, in the way well known to those skilled in the art. 75

Also, the shaft 7, through the wrist pin 30, on eccentric 31, traveling in the slot 32, in the slide 35, moving in guides 36, 37 in the head plate 33 of the machine, raises and lowers the slide 35, which is provided with 80 a forked bracket arm 38, carrying a nut 39, meshing with the worm 40 on the tube 41, which is provided with shoulders 42, 43 to prevent its slipping up or down in the channel through the parts of the composite, rotatable spindle, which adjusts the position of the stitch forming element above the fabric relative to the direction of the fabric feed, as will be explained. 85

A hollow spindle 44 extends down 90 through brackets 45, 46 on the head plate 33, and at its lower end is provided with a collar 47, a tube 48, extends down through another bearing 49 on the head plate, which is provided with a sleeve 50. At its upper 95 end the tube 48 is provided with a flange 51. And two rods 52, 53 are firmly inserted in the collar 47 and the tube 48 so as to connect them as an unitary structure.

These rods 52, 53 extend through holes in 100

the nut 39, so that the nut may slide up and down upon them without turning. The result of this arrangement is that when the nut 39 is raised or lowered, the tube 41 will 5 be revolved within the composite spindle.

To the lower end of the tube 48 is secured a collar 54, carrying an arm 58, terminating in a cleft resistance foot 56 normally positioned just above the plane of the fabric.

10 The collar 54 also carries a shank 57 at the lower end of which is the bead separator 58, which has a portion 69 depressed, about the length of a bead, below its general surface level and leading under a spiral 15 shoulder extending down toward the conical point.

To the shank 57 is secured a cam rod 59 the function of which will be explained later. At the lower end of the tube 41 is 20 secured a collar 60, which carries the looper 61, the lower end of which is provided with a guide box 62, lying so near to the bead separator that when the looper travels around the bead separator 58, there shall not 25 be normally sufficient space for a bead to pass down between the flat upper edge of the separator and the back of the box 62, (see Fig. 16).

The back stop or lateral guard 63 of the 30 looper is carried by a spring 64 and is extended down so that it is outside of the bead, which rests on the depressed surface of the separator; and it prevents the bead from falling out over the edge of the depressed 35 part of the separator. But in case a bead should become jammed between the looper and separator the back stop will yield outward, so as to avoid serious damage.

A bead follower or guard 66, is carried 40 by a spring shank 67, secured to the collar 60, and is provided with a back stop 68 which limits the normal backward action of the spring shank. The follower 66 extends down near to the depressed upper surface 45 69 of the separator, so that it lies behind a bead which rests upon that surface. The curve of the rod 59 is such that when the looper and follower are in their initial stitch position, as in Fig. 16, the follower 50 will be pressed in close to the shoulder of the raised, flat top of the bead separator, and, as the looper and follower move around the separator, the follower will pursue the irregular curve of the flat upper edge of the 55 separator, at a slight distance therefrom, and will push before it, and under the spiral shoulder 71, the bead which may be in front of the follower. Thus, it will be seen, the improved looper prevents more than one 60 bead from passing the separator for each stitch movement of the looper, and also prevents the bead from falling out over the side of the separator. If, for instance, the thread should be unduly slack; and the bead follower 65 lower keeps the bead from lagging back

of the looper and getting out of position, and pushes the bead forward under the steep portion of the separator's shoulder, where it will certainly travel down to the fabric in proper relation to the stitch which is being 70 formed. The limits of travel of the looper are marked by 87, and 88, Fig. 10.

To the lower end of the feeder-bar, which may be raised, lowered and swung backward and forward in the usual way, is secured a feeder foot, preferably of an annular form, and provided with a shoe 120, having a yieldable or elastic portion, for instance the multiplicity of flexible elements 122, 122, adapted to straddle the beads, and to yield slightly laterally, and to bear with an elastic pressure against the fabric so as to accomplish the feeding operation without injuring the beads or fabric.

In order that the beads shall be properly fed to and past the bead separator, it is necessary that they shall be supplied to the separator without interruption and at a uniform rate, neither too many nor too few being let down through the tube 41 to the 20 separator.

The thread upon which the beads have been strung loosely, so that the beads may be separated at considerable intervals on the thread, to allow the necessary thread to form the stitches, is wound around a drum 150, carried upon bracket arms 151 above the machine, and is lead from there down through a trough-like guide 152, provided with transverse ribs 153, 154, against which the thread from the drum 150 will normally be held down by the weight of the beads upon it, so that the beads will be arrested temporarily by and held above the flanges, while the thread may move downward through the beads.

It is often desirable to wind several threads, with different colors or styles of beads on them, on different sections of the drum 150, so that they may be used selectively by the operator; and the conformation of the trough 152 is such that a thread may be lead, from any point on the circumference of the drum, directly to the narrow end of the trough, and on to the bead separating sprocket, without interference from the sides of the trough. The vibration incident to the operation of the machine will cause the beads from time to time to slip past the flanges and to travel down to the bead feeders, and if they should not do so, a slight jarring of the trough or thread by the operator will produce the desired movement. Beyond the lower, narrowed end 155 of the trough 152 is a sprocket wheel 156, the arms 157 of which are spaced to accommodate a bead between every two of them, and may be provided with a cross groove 158 to receive the thread between the beads. And immediately below the end of 130

the trough is arranged a pair of vertically reciprocating bead feeders which are operated as follows:—

10 The feeder 161 is carried by a rocking bar 163, pivoted at 164 upon a bracket 165 on the arm 3 of the machine, and is connected by a rod 166 to the arm 167 of a bell crank, the other arm 168 of which travels against the cam 31 and is held to duty by a spring 86 extending from it to the arm 85 of a bell crank 83, 85. Consequently, with each revolution of the shaft 7, the bead feeder 161 will be raised and lowered once.

15 The bead feeder 162 is carried by a rocking arm 170, pivoted at 171 to the bracket 165, and connected by a rod 172 with the arm 83 of the bell crank 83, 85, the free arm of which also travels against the cam 20 wheel 31. And through this means the bead feeder 162 is also raised and lowered, once for each revolution of the shaft 7, but alternately with the feeder 161.

25 The beads, normally follow the thread, down to the feeder blade 161, and when it is lowered they slide forward against the feeder blade 162. When the blade 161 rises, it passes normally between the bead which is resting against the blade 162 and the bead 30 next above it, holding back the latter and permitting the former to pass on to the sprocket wheel when the blade 162 is lowered. And if a blade in rising should hit below a bead, instead of passing it, the bead 35 and thread will simply be lifted by the blade, to be lowered again when the reverse movement takes place; and the proper feeding of the beads will then continue without injury to the beads or thread or to the machine.

40 To the free end of the rocking bar 163 is attached a pawl 175, pressed to duty by a spring, as 176, or other suitable means, and adapted to engage with a ratchet wheel 45 177 on the hub 178 of the sprocket wheel 156, which is carried upon a shaft 179 in the end of a rocking bar 183. On the end of the shaft 179 is placed a screw cap 180, which is omitted for clearness in Fig. 7. 50 And between the cap 180 and the hub of the sprocket wheel 156 is interposed a coiled spring 181, by the compression of which the sprocket wheel may be braked.

55 One end of the rocking bar 183, pivotally mounted on the bracket 165, is normally held down, by a spring 185, against the upper end of a rod 195 which rests above one arm 194 of a bell crank, the other arm 192 of which carries a roller 193 traveling 60 against a cam 190 on shaft 7. The eccentric portion of the cam is short and so formed as to give a quick movement to the arm 192 when the cam is rotated. The roller is kept to duty by a spring 198.

65 In the operation of the machine, the beads

will be gradually fed, along the thread, to the bead feeders, and past them at the rate of one bead for each stitch made by the machine; and they will be passed by the positively actuated ratchet-fed sprocket feed-wheel at the same rate, and so will slide down along the thread, through the hollow spindle, to join the beads passing through the looper to the bead separator, thus keeping up a uniform succession of 75 beads to the latter point, and preventing their accumulating between the bead feeders and the ratchet wheel.

The lowest bead is carried down along the bead separator groove, when the looper swings around the separator to cast the loop around the needle, being kept from falling out, over the side of the separator, by the back stop of the looper, and being pushed forward, and prevented from lagging behind and distorting the thread or stitch loop, by the bead follower which follows closely behind the looper. At the same time the other beads on the thread passing through the looper will be held up by the upper, flat 80 surface of the bead separator, the edge of which will cut in between the lowermost bead and the one next above it, as the looper moves around the separator.

85 While the needle is raised through the nipple and fabric, the nipple will remain raised, so as to press the fabric up against the foot of the arm 55 thereby holding the loop of thread, through which the needle rises to make the next stitch, firmly in place 90 between the nipple and fabric, so that, when the needle descends it will draw the new loop through the old loop without danger of the barb of the needle catching the old loop the second time.

100 Just as the needle is about to descend to carry down the new loop the thread will be given a quick upward jerk by the arm 183, snugging up the thread around the shank of the needle so as to insure its catching under the barb of the needle.

105 It will be understood by those skilled in the art, that details of construction may be modified by the use of mechanical equivalents or the like without departing from the spirit of my invention as claimed.

110 Having thus described my invention, what I claim and desire to secure by Letters Patent of the United States, is:—

1. The combination, in a bead sewing machine embodying a reciprocating needle, and a bead-separator, of a cooperating, rotatable looper, and a lateral bead guard associated with the looper.

120 2. The combination, in a bead sewing machine embodying a reciprocating needle, and a bead-separator, of a cooperating looper, and a lateral bead-guard carried below the looper.

125 3. The combination, in a bead sewing ma-

chine embodying a reciprocating needle, and a bead-separator, of a cooperating looper, and a bead follower associated with the looper.

5 4. The combination, in a bead sewing machine embodying a reciprocating needle, a bead-separator, and a cooperating looper, of a lateral bead-guard below the looper, and a cooperating bead follower.

10 5. The combination, in a bead sewing machine embodying a reciprocating needle, a bead-separator, and a cooperating looper, of a bead follower associated with the looper, and an elastic means supporting the follower.

15 6. The combination, in a bead sewing machine embodying a reciprocating needle, a bead-separator, and a cooperating looper, of a lateral bead-guard and elastic supporting means therefor.

20 7. The combination, in a bead sewing machine embodying a reciprocating needle, a bead-separator, and a cooperating looper, of side and back bead-guards associated with the looper.

25 8. The combination, in a bead sewing machine, embodying stitch forming mechanism, of a reel, a fixed guide provided with fixed bead-arresters, and movable bead feeding means.

30 9. The combination, in a bead sewing machine, embodying stitch forming mechanism, of a reel, a guide consisting of a uniformly tapered trough provided with fixed, transverse, bead-arresters, and movable bead feeding means.

35 10. The combination, in a bead sewing machine, embodying stitch forming mechanism, of a thread reel for holding the strung beads, and means embodying alternately operable, vertically reciprocable elements, disposed horizontally below and transversely of the thread, for feeding the beads one by one along the thread toward the stitch forming mechanism.

40 11. The combination, in a bead sewing

chine embodying stitch forming mechanism, and bead separating mechanism associated therewith, of means for drawing forward a thread with beads loosely strung thereon, rotatable, driven means for feeding one bead forward toward the bead separating mechanism for each stitch, and driving means for actuating said rotatable means.

45 12. The combination, in a bead sewing machine, embodying stitch forming mechanism and thread and bead supplying mechanism, of a bead feeder consisting of a sprocket wheel having grooved arms, a pawl and ratchet, and means for actuating the same to cause such sprocket wheel to feed forward one bead for each stitch.

55 13. The combination, in a bead sewing machine, embodying stitch forming mechanism, of strung-bead supplying mechanism, vertically reciprocating means for feeding the beads one by one along the thread, and positively actuated rotating means for passing one bead toward the stitch forming mechanism for each stitch and means for actuating said rotating means step by step.

60 14. The combination, in a single thread bead sewing machine, of stitch forming means, positively actuated bead feeding and forwarding means, loop tightening means, loop holding means, and elastic feeding means.

65 15. The combination, in a single thread bead sewing machine, of stitch forming means, positively actuated bead feeding and forwarding means, bead separating means, loop tightening means, loop holding means, and elastic feeding means.

70 16. The combination, in a single thread bead sewing machine, of stitch forming means, positively actuated bead feeding and forwarding means, bead separating means, loop tightening means, loop holding means, elastic feeding means, and bead following and guarding means.

JOSEPH A. GROEBLI
